Primary Examiner — John A Voytek(74) *Attorney, Agent, or Firm* — Mark D. Bowen, Esq.; Malin Haley DiMaggio & Bowen, P.A.(57) **CLAIM**

The ornamental design of a marine air conditioner enclosure, as shown and described.

DESCRIPTION

FIG. 1 is a top perspective view of a marine air conditioner enclosure in accordance with the present invention;

FIG. 2 is a bottom perspective view thereof;

FIG. 3 is a top view thereof;

FIG. 4 is a bottom view thereof;

FIG. 5 is a front view thereof with the rear view, left side view, and right side view, being identical; and,

FIG. 6 is a top perspective view illustrating a marine enclosure installed on a marine vessel.

The broken lines in FIGS. 2 and 4 form no part of the claimed design. The broken lines in FIG. 6 showing the marine vessel are directed to the environment and form no part of the claimed design.
